US0D1032612S

(12) **United States Design Patent** (10) **Patent No.:** **US D1,032,612 S**
(45) **Date of Patent:** ** *Jun. 25, 2024

(54) **AUTO-EMPTYING DOCKING STATION**

(71) Applicant: **SHARKNINJA OPERATING LLC**, Needham, MA (US)

(72) Inventors: **Junghwan Chei**, Chestnut Hill, MA (US); **Owen R. Johnson**, Needham, MA (US); **Scott B. Niedzwecki**, East Walpole, MA (US); **Kyu Lee**, Bedford, MA (US)

(73) Assignee: **SharkNinja Operating LLC**, Needham, MA (US)

(*) Notice: This patent is subject to a terminal disclaimer.

(**) Term: **15 Years**

(21) Appl. No.: **29/820,677**

(22) Filed: **Dec. 23, 2021**

Related U.S. Application Data

(63) Continuation of application No. 29/695,065, filed on Jun. 14, 2019, now Pat. No. Des. 939,436.

(57) **CLAIM**

The ornamental design for an auto-emptying docking station, as shown and described.

DESCRIPTION

FIG. 1 is a front view of an auto-emptying docking station, showing the new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front, top right perspective view thereof;

FIG. 8 is a front, bottom right perspective view thereof;

FIG. 9 is a rear, top left perspective view thereof;

FIG. 10 is a rear, bottom left perspective view thereof;

FIG. 11 is a right, top front perspective view thereof;

FIG. 12 is a right, bottom front perspective view thereof;

FIG. 13 is a left, top front perspective view thereof; and,

FIG. 14 is a left, bottom front perspective view thereof.

The broken lines in the figures show portions of the auto-emptying docking station that form no part of the claimed design.
